CLAIM

The ornamental design for an apparatus for extension of function of electronic computers, as shown and described.

DESCRIPTION

FIG. 1 is a top, front and right side perspective view of an apparatus for extension of function of electronic computers showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a right side elevational view showing the article in use.

The broken lines are for illustrative purposes only and form no part of the claimed design.
